Primary Examiner — Selina Sikder

(57) **CLAIM**

I claim the ornamental design for remote-controlled servo, as shown and described.

DESCRIPTION

FIG. 1 is a three-dimensional view of an embodiment of remote controlled servo showing my new design;

FIG. 2 is a right side elevational view of the embodiment;

FIG. 3 is a top plan view of the embodiment;

FIG. 4 is a front elevational view of the embodiment;

FIG. 5 is a bottom plan view of the embodiment;

FIG. 6 is a left side elevational view of the embodiment; and,

FIG. 7 is a rear elevational view of the embodiment.

1 Claim, 4 Drawing Sheets

FIG. 1

FIG. 2

FIG. 3

FIG. 4

FIG. 5

FIG. 6

FIG. 7
